UNITED STATES PATENT OFFICE.

RAYMOND N. EHRHART, OF PITTSBURGH, PENNSYLVANIA, ASSIGNOR TO ELLIOTT COMPANY, OF PITTSBURGH, PENNSYLVANIA, A CORPORATION OF PENNSYLVANIA.

CENTRIFUGAL PUMP.

Application filed May 3, 1927. Serial No. 188,469.

The present invention relates broadly to the art of air and gas pumps and more particularly to a centrifugal pump of the character adaptable for use in connection with jet condensers.

Under certain conditions encountered in regular commercial operation, centrifugal pumps of the general character herein contemplated are called upon to handle fluids which are highly impregnated with acid or other corrosive or erosive materials or substances. In order to meet this condition effectively, it has heretofore been proposed in the art to construct the entire pump of a material capable of resisting corrosion or erosion. This procedure, however, is extremely expensive because of the greater cost of the materials thus required as compared to the cost of cast iron which is frequently used.

In jet condensers which may, for example, be of the general construction illustrated in my Patent No. 1,533,840, granted April 14, 1925, this matter has heretofore frequently required the use of extremely expensive pump structures. This is true partly by reason of the fact that in such condensers the water is heated before it gets to the pump, whereby the action referred to is more virulent than is the case with ordinary pumps. Inasmuch as large jet condensers require quite large pump installations, it is highly desirable, if possible, to avoid constructions requiring the entire pump to be constructed of acid resisting materials.

In accordance with the present invention there is provided an improved pump structure in which only that portion of the pump subjected to high water velocities where the erosion and corrosion present a really serious problem, are of special design and construction not only to effectively resist such action, but to facilitate removal or replacement thereof as may be necessary.

In the accompanying drawings, there is shown, for purposes of illustration only, a preferred embodiment of the present invention, it being understood that the drawings do not define the limits of my invention as changes in the construction and operation disclosed therein may be made without departing either from the spirit of the invention or the scope of my broader claims.

In the drawings,

Fig. 1 is a vertical sectional view through

one form of jet condenser and centrifugal pump serving the same in accordance with the present invention; and,

Fig. 2 is a view on an enlarged scale, partly in section and partly in elevation, illustrating more particularly the pump structure.

The jet condenser and pump arrangement, illustrated herein, while capable of assuming a wide variety of different shapes and arrangements, may be of the general nature shown in my patent previously referred to. In such cases, the housing 2 of the pump supports the jet condenser structure 3, thereby making it extremely difficult to effect removal of the pump as a whole from its foundation as is now required to replace the different parts thereof.

In accordance with the present invention, one wall of the housing 2 is provided with an offset member or members 4 providing in effect a series of sockets 5. These sockets are constructed in such manner that they effectively cooperate with the section A of the pump constituting part of the volute and discharge therefor. The section A may be secured in position within the housing in any desired manner as for example, by bolts 6 passing through the offset members 4.

The portion 7 of the housing illustrated more particularly in Fig. 2 of the drawings, is machined to provide a true face preferably lying in a plane intersecting the longitudinal axis of the centrifugal pump, and the section A is of such construction that its outer face which is also preferably machined, coincides with the face 7.

The remainder of the volute and discharge for the pump, comprises a section B in the form of a cover having a machined face 8 cooperating with the machined face 7 on the pump housing and the machined face coinciding therewith on the pump section A. The cover section B is entirely exteriorly located with respect to the housing 2 while the section A is interiorly located relatively thereto.

The sections A and B may be of any desired metal having such characteristics as to more effectively resist the corrosion or erosion referred to. When constructed as disclosed herein, access to the pump structure is permitted by the removal of the cover section B which may, if desired, be replaced at will, and removal of the entire pump from

its bearings and consequently removal of the section A is permitted by reason of splitting the sections along a line coinciding with the major axis of the housing and intersecting the axis of the pump shaft and the bearings therefor as illustrated in Fig. 2.

Certain advantages of the present invention arise not only from the utilization of relatively more durable material from the standpoint of corrosive or erosive action, but from the provision of sections of such material, which sections are of such nature as to facilitate removal thereof.

Further advantages of the invention arise from the provision of sections of the nature referred to, split along the major axis of the housing and constructed in such manner that the outer face of the section supported within the pump housing coincides with the machined face thereon.

Still further advantages of the invention arise from the provision of a pump section constituting part of the volute and discharge therefor supported within depressions or sockets formed on the pump housing.

I claim:

1. A centrifugal pump, comprising a housing receiving the water supply for said pump, and a volute and discharge member for said pump comprising separable sections removably secured to said housing, one of said sections being located within the housing and the other of said sections being exteriorly secured to said housing.

2. A centrifugal pump comprising a housing receiving the water supply for said pump, and a volute and discharge member for said pump split along the major axis of said housing and in a plane substantially parallel to and including the axis of the volute to form sections independently removable therefrom.

3. A centrifugal pump comprising a housing receiving the water supply for said

pump, and a volute and discharge member split along the major axis of said housing to form sections independently removable therefrom, one of said sections being positioned within the housing and the other of said sections being exteriorly secured thereto.

45

4. A centrifugal pump comprising a housing having a machined face, said housing being adapted to receive the water supply for said pump, and a volute and discharge member for said pump comprising sections secured to said housing, said sections being split in such manner that the cooperating faces thereof coincide with the machined face on said housing.

55

5. A centrifugal pump comprising a housing having a machined face, said housing being adapted to receive the water supply for said pump, and a volute and discharge member comprising sections secured to said housing, said sections being split in such manner that the cooperating faces thereof coincide with the machined face on said housing, one of said sections being detachably supported within the housing and the other of said sections being exteriorly secured thereto.

65

6. A centrifugal pump comprising a housing having a machined face, said housing being adapted to receive the water supply for said pump, and a volute and discharge member comprising sections secured to said housing, said sections being split in such manner that the cooperating faces thereof coincide with the machined face on said housing, one of said sections being detachably supported within the housing and the other of said sections being exteriorly secured thereto, said first mentioned section being socketed within said housing to terminate substantially flush therewith.

75

In testimony whereof I have hereunto set my hand.

80

RAYMOND N. EHRHART.
